ROTARY JAR

Ferdinand J. Spang, Butler, Pa.

Application October 13, 1932, Serial No. 637,569

12 Claims. (Cl. 255—27)

This invention relates to a jar for drilling operations for loosening and removing a bit or other parts of the drill string from a well, and more particularly to improvements in a jar suitable for use in the rotary method of drilling.

In the rotary method of drilling, the drilling is accomplished by constantly rotating a bit through force generated at the surface and transmitted to the drill bit at the bottom of the well through a series of tubular drill pipe sections.

During the drilling operation mud laden water is pumped through the drill pipe to the bit and carries the cuttings of the formation being drilled to the surface through the space between the drill pipe and the bore of the well.

It is not an uncommon occurrence during the process of drilling for the bit and lower sections of the drill pipe to become fast or stuck in the well due to crevices and other irregularities developing in the bore holes and from escapement or loss of the mud laden water through porous formations. When such occurs it is frequently impossible to withdraw the tubing and bit from the well by a straight upward pull, however, they may be quickly released by jarring thereby avoiding the necessity of destroying them in order to effect their removal.

To secure this jarring action, it is customary to interpose what is commonly known as a jar at a suitable point in the string of tubular drill pipe usually in the lower sections thereof relatively close to the bit. The jars now generally used are formed of two elements, one of which is capable of limited longitudinal movement relative to the other to produce the jarring actions. Such jars have not proven altogether satisfactory because it is impossible to raise the movable element fast enough to create an impact of sufficient force to loosen the bit or other tool stuck in the well and also because the elements of the jar become packed or clogged with sand cuttings and other débris occasioned by the drilling operations and, as a result the jarring elements become tightly locked together, making the jar inoperative.

It is an object of this invention to provide a simple rugged jar, suitable for use with rotary drilling tools, having telescoping jarring elements releasably locked together in their fully telescoped position, the elements being automatically released for limited relative movement when subjected to a predetermined stress sufficient to cause a stretching in the drill pipe, whereby a definite amount of energy may be stored up in the tubular drill pipe prior to the release of the ele-

ments which causes it to return rapidly toward normal condition when the elements are released; and providing for the definite arrestment of the relative movement of the jarring elements thus transmitting to the stuck bit or drill pipe a considerable portion of the developed inertia in the form of a jar.

Another object is to provide a jar suitable for use with rotary drilling tools having exceptionally rugged jarring elements and means for keeping the striking faces thereof free of sediment and débris and means for expelling the fluid and débris from between the striking faces when a blow is struck.

Another object is to provide a jar suitable for use with rotary drilling tools having means for transmitting the rotative force through the plunger direct to the lower sections of the drill pipe, thus permitting full use of the plunger head for a striking face and for a guide against angular deflection.

A further object is to provide a jar suitable for use with rotary drilling tools having rugged, simple means for releasably locking the jarring elements together, which means are automatically operative, releasable upon an upward pull of a definite determined force, and lockable upon slight compression force so that successive jarring blows may be struck.

A still further object is to provide a jar suitable for use with rotary drilling tools having a releasable locking element for locking the jarring elements together, which locking means cannot be rendered inoperative by the packing of sand and débris in and around it.

A still further object is to provide a jar suitable for use with rotary drilling tools having a simple means for releasably locking the elements together which means are located within the flow-course of the circulating fluid so that it will be constantly washed free of sand and débris and that the movement of the releasable locking means will be unrestricted by other parts of the jar or by sand or débris.

A still further object is to provide a jar suitable for use with rotary drilling tools having a simple automatically releasable locking means rugged of construction, easily assembled, positive in operation, and operative either while the elements are being rotated or in a non-rotating position.

These and other objects which will be herein-after made readily apparent to those skilled in this particular art are accomplished by means of this invention, one embodiment of which is de-

scribed in the following specification and illustrated in the accompanying drawing, wherein:

Figure 1 is a vertical section of my improved jar showing the jarring elements releasably locked in drilling position;

Fig. 2 is a vertical section of the jar showing the position of the jarring elements when the mandrel has been pulled upwardly to produce a jarring impact;

10 Fig. 3 is an enlarged view partially in elevation and partially in section of the member for releasably holding the jarring elements in drilling position;

Fig. 4 is an enlarged elevation of the lower 15 end of the mandrel;

Fig. 5 is an enlarged vertical section of the lower connecting sub; and

Fig. 6 is a section taken on line VI—VI of Figure 1.

20 In general, a rotary jar made in accordance with my invention comprises two cylindrical jarring elements, one of which is telescopically mounted in the other and is capable of limited longitudinal movement relative thereto so that

25 when the jar is interposed in the drill string, the drill pipe may be moved upwardly to bring the two elements into striking relation and produce a jarring action on the bit or other tool fast in the well. To increase the impact of the

30 jarring elements, I provide a member for normally locking the two elements in their fully telescoped or contracted position, which is adapted to automatically release when a predetermined stress, sufficient to cause a stretching in the drill 35 pipe, has been applied thereto, so that the energy developed by the stretching of the drill pipe will be utilized to bring the two elements together with sufficient force to impart an exceedingly heavy jarring blow on the bit or other tool.

40 This locking member may be so designed that any predetermined or desired amount of stretching will take place in the drill pipe before the jarring elements will be released to produce the jarring impact.

45 To avoid any possibility of the member locking the jarring elements together becoming packed or clogged with sand and other cutting debris and thereby making the jar inoperative, the locking member is so disposed in the jar 50 that it is constantly washed with the mud laden water being pumped through the drill pipe to the bit, which effectively prevents the drill cuttings from wedging around the locking member. To provide for definite freedom of action, the path 55 of travel of the locking member as it releases, is away from the working parts of the jar.

Referring to the drawing in detail, 10 indicates a jar made in accordance with my invention which is adapted to be interposed in a rotary 50 drilling string between the bit and the tubular drill pipe. The jar 10 comprises an outer cylindrical shell 11 having a tubular connecting sub 12 threaded to the lower end thereof for connecting it to a drill bit or other tool (not shown).

65 Slidably mounted for limited longitudinal movement within the shell 11 is a cylindrical mandrel 13 the upper end of which is connected to a tubular sub 14 for joining it to the lower end of the drill pipe (not shown) through which rotary 70 motion is transmitted to the drill bit. In order that the rotative force generated on the surface will be transmitted through the jar, the lower end of the mandrel has a series of splines 15 on the outer surface thereof which engage with splines 16 on the inner surface of a portion 12a

of the sub 12, thus making a direct drive from the drill pipe to the bit or tool secured to the sub. These splines 15 and 16 are so designed that they are always in engagement regardless of the longitudinal position of the mandrel in the shell 11 whereby any rotation of the mandrel will always be transmitted to the bit or other tool. The mandrel 13 is provided with a longitudinally extending passageway 17 through which the mud laden water pumped through the drill pipe is conveyed to the drill bit.

The longitudinal sliding movement of the mandrel 13 within the shell 11 is limited in one direction by the end of the mandrel striking against the portion 12a of the sub 12 and in the opposite direction by a shoulder 18 on the outer surface of the mandrel which engages a shoulder 19 on the inner surface of the shell. This shoulder 18 forms a hammer which is adapted to strike against the shoulder or anvil 19, when an upward pull is placed on the drill pipe, to produce a jarring impact for loosening the tool fastened to the connecting sub 12.

In order to increase the impact with which the hammer 18 strikes the anvil 19, I provide means 100 for locking the mandrel against longitudinal movement relative to the shell, which are adapted to automatically release the mandrel when an upward pull of sufficient force to cause a stretching in the drill pipe has been applied thereto 105 whereby the energy released by the contracting of the drill pipe will be utilized to suddenly move the hammer against the anvil and impart an exceedingly heavy blow to the tools fast in the well. This locking means which is disposed in 110 the passageway 17, of the mandrel 13 and connected to the portion 12a of the sub 12, comprises a cylindrical member 20 having a series of longitudinally extending slots 21 intermediate of its length forming a series of leaf springs 22 connected together at each end by collars 23. Each of these leaf springs 22 has a beveled latch 24 formed thereon which is adapted to seat over a sloping face 25 of a groove 26 formed on the inner surface of the mandrel 13 and normally 115 hold the elements of the jar in drilling position (Fig. 1).

From this construction it is apparent when the bit or lower end of the drill string become stuck or fast in the bore hole, the jar 10 is actuated to loosen the stuck tools by a straight upward pull on the drill pipe. This upward movement of the drill pipe is transmitted to the mandrel 13 and causes the latches 24 to slide on the surface 25 and bend the leaf springs 22 inwardly. 120 When the upward pull applied to the drill pipe reaches a predetermined stress, the latches are 125 designed to release the mandrel and permit it to move rapidly upward so that the hammer 18 strikes against the anvil 19 arresting the movement of the mandrel and imparting a jarring impact to the bit or tools carried by the sub 12.

If one impact is insufficient to loosen the bit or tool fast in the bore hole, the drill pipe is 130 lowered and the weight thereof causes the mandrel to move downwardly until the lower end strikes the portion 12a of the sub at which time the latches 24 again seat over the sloping face 25 on the mandrel and the jar is then in position to be again actuated to impart another 135 jarring blow to the drill or other tool.

So that a stretching action will take place in the drill pipe, the cylindrical member 20 is so 140 designed and is of such material and size that 145

the latches 24 remain seated against the surface 25 until a predetermined upward force has been applied to the drill pipe. By making the locking member in the form of a cylindrical series of leaf springs supported at both ends, the angle between the beveled latches and the sloping surface on the mandrel remains substantially the same regardless of the degree of compression of the springs. As a result a constantly increasing force is necessary to fully compress the springs to permit the latches 24 to disengage or slide off the surface 25. Thus, it is apparent that with my improved spring member a predetermined amount of stretching will occur in the drill pipe before the spring releases the mandrel.

So that the springs 22 will not become packed or clogged with sand and other cutting débris, the cylindrical member 20 is so disposed within the passageway 17 of the mandrel that the leaf springs 22 will be continually washed by the mud laden water pumped through the drill pipe. By so locating the cylindrical member 20, the springs 22 are caused to move inwardly into the passageway 17 to release the mandrel and, as a result, the movement of these leaf springs will not be restricted by the other parts of the jar, or by sand and other débris and it is impossible for the jar to become clogged and inoperative.

To insure a clean striking surface on the hammer 18 so that a solid blow will be struck against the anvil 19, passageways 27 and 28 are formed in the mandrel 13 which lead from the shoulder 18 to the passageway 17 and permit the sand and other débris which has worked into the jar between the shell and the mandrel, to be washed away from the hammer 18. The water for washing the hammer is forced through openings 29 drilled at an angle through the wall of the mandrel above a reduced bore portion 17a of the passageway 17. This reduced bore 17a tends to retard the flow of water through the passageway 17 and forces a portion thereof through the openings 29 which deliver it to the shoulder 18 and from which it is carried back into the passageway 17 through the passageways 27 and 28.

To prevent leakage of the mud laden water and to keep sand and other débris from collecting between the shell and the mandrel, the interior of the upper end of the shell is made larger in diameter than the central portion thereof to receive a packing 30 and a packing gland 30a which is threaded to the inner wall thereof and surrounds the cylindrical mandrel 13. This packing gland may be readily held in place by a set screw 31 extending through the wall of the shell.

From the foregoing description, it is readily apparent that I have designed a rotary jar which when operated will cause an exceedingly heavy blow to be transmitted to the tools fast in the bore hole since a constantly increasing force, sufficient to stretch the drill pipe to a predetermined stress point, may be applied to the drill pipe before the elements of the jar will release. When the cylindrical leaf springs have been compressed sufficiently to suddenly release the jarring elements, the two come together with extreme force, due to the sudden removal of strain in the drill pipe, so that the stored up energy of the drill pipe is utilized in producing the jarring impact.

It is also apparent that my improved jar is of simple and rugged construction, has few parts to get out of order and since sand and other cutting débris are continually washed away from the working parts, the jar cannot become packed or

clogged and consequently, is always capable of being operated.

While I have described one embodiment of my invention, it is to be understood that certain changes, modifications, substitutions and omissions may be made therein without departing either from the spirit of my invention or the scope of the appended claims.

What I claim as new and desire to secure by Letters Patent is:

1. A rotary jar comprising an outer shell having an anvil formed on the inner surface thereof, a cylindrical mandrel slidably mounted in said shell and having a longitudinally extending passageway therein, a hammer on said mandrel, means permitting limited longitudinal movement between the shell and the mandrel, and means normally holding said mandrel and shell against relative longitudinal movement and releasing under predetermined pull to permit the hammer to strike said anvil and set up a jarring action, said last-mentioned means including a cylindrical member associated with said shell and extending into the tubular mandrel, said cylindrical member having a series of longitudinally extending slots therein forming a series of leaf springs terminating at each end in an integral collar, and a beveled latch member on each of said leaf springs adapted to seat over a sloping face on the inner surface of said mandrel, the latch member on each of said leaf springs being so arranged that substantially the same angle is maintained between the beveled surfaces and the sloping face on the mandrel when the leaf springs are depressed whereby a constantly increasing pull is necessary to release the mandrel.

2. A rotary jar comprising an outer shell, a tubular sub connected to the end of said shell, a mandrel slidably mounted in said shell, and having a longitudinally extending passageway therein, interengaging means on said sub and mandrel for preventing rotation of said mandrel relative to said sub, means secured to said sub and extending into the passageway in said mandrel for releasably holding said mandrel against longitudinal movement relative to said shell, and means for arresting the movement of said mandrel when said holding means have been released to impart a jarring blow to said shell.

3. The invention as claimed in claim 2, in which a cylindrical series of leaf springs is connected to the sub and extends into the passageway in the mandrel for releasably holding the mandrel against longitudinal movement relative to the shell.

4. The invention as claimed in claim 2, in which a cylindrical member having a plurality of longitudinally extending slots is connected to the sub and extends into the passageway in said mandrel and each portion of the cylindrical member between the slots is provided with a latch for releasably holding the mandrel against longitudinal movement relative to the shell.

5. The invention as claimed in claim 2, in which a longitudinally slotted member having a series of latches on its outer surface adapted to seat in a groove formed on the mandrel, is utilized for releasably holding the mandrel against longitudinal movement relative to the shell.

6. A rotary jar comprising an outer shell having a shoulder on the inner surface thereof, a mandrel telescopically mounted for limited longitudinal movement in said shell and having a shoulder thereon for engaging the shoulder on

said shell to arrest the movement thereof, said mandrel having a longitudinally extending water passageway therein and a series of openings formed in the wall thereof, at different elevations along its length, connecting said passageway with the outer surface thereof, means for forcing water to pass to the exterior of said mandrel through the upper of said openings and back into said passageway through the lower of said openings, whereby the shoulder on said mandrel will be kept free of sand and other débris.

7. A rotary jar comprising an outer shell, a mandrel telescopically mounted for limited longitudinal movement in said shell and having a longitudinally extending water passageway therein, a shoulder on said mandrel, said mandrel having a series of openings therein above said shoulder connecting said passageway with the outer surface of the mandrel, and a series of openings leading from the face of said shoulder into said passageway, and a reduced bore portion in said passageway between said upper and lower series of openings whereby a portion of the water in said passageway is forced through the upper series of openings onto said shoulder and returned to said passageway through the lower of said openings.

8. A rotary jar comprising an outer shell, a mandrel telescopically mounted for limited longitudinal movement in said shell and having a longitudinally extending water passageway therein, and means for arresting the longitudinal movement of said mandrel relative to said shell, said mandrel having an upper and lower series of openings in the wall thereof for diverting a portion of said water from said passageway to cleanse said arresting means.

9. A rotary jar comprising an outer shell, a mandrel slidably mounted on said shell and having a longitudinally extending water passage therein, means for releasably locking said mandrel against movement in said shell, means for arresting the movement of said mandrel when it has been released, means for cleansing the arresting means, and means for retaining the cleansing means within said jar.

10. A rotary jar comprising a shell, a mandrel telescopically mounted within said shell for longitudinal movement relative thereto from a nor-

mal contracted position to an expanded position, coacting surfaces on said mandrel and shell interengageable to arrest movement of said mandrel when in expanded position, said mandrel having a longitudinally extending water passageway therein and a series of openings formed in the wall thereof, a latching member for locking said mandrel in its contracted position, adapted to release on application of a predetermined force, said latching member being disposed in the water passageway in the mandrel whereby débris is continually washed therefrom, and means for circulating washing water through the openings in said mandrel to cleanse said coacting surfaces.

11. A rotary jar comprising a shell, a mandrel telescopically mounted for longitudinal movement within said shell, said mandrel having a longitudinally extending water passageway therethrough and a series of openings in the wall thereof connecting the inner and outer surfaces thereof, means for arresting the longitudinal movement of said mandrel, and a cylindrical latching member adapted to lock said mandrel in its contracted position and release the mandrel on application of a predetermined force thereto, said latching member being disposed in said passageway whereby débris is continually washed therefrom, a portion of said passageway in said mandrel being of reduced bore to build up a back pressure in said passageway and cause water to flow through the openings in said mandrel and cleanse the arresting means.

12. A rotary jar comprising a shell having a shoulder on the inner surface thereof, a mandrel telescopically mounted for limited longitudinal movement within said shell and having a shoulder thereon for engaging the shoulder on said shell to arrest the movement thereof, said mandrel having a longitudinally extending water passageway therein, and a series of openings in the wall thereof on each side of said shoulder, a reduced bore portion in said passageway between the series of openings and a cylindrical spring latching member adapted to release upon application of a predetermined force thereto, for normally locking said mandrel in its contracted position within said shell, said latching member being disposed in said water passageway whereby it is continually subjected to a washing liquid.
